UNITED STATES PATENT OFFICE.

WILLIAM LOUDEN, OF FAIRFIELD, IOWA.

CATTLE-STALL.

1,236,326.

Specification of Letters Patent.

Patented Aug. 7, 1917.

Application filed July 31, 1913. Serial No. 782,274.

To all whom it may concern:

Be it known that I, WILLIAM LOUDEN, residing at Fairfield, in the county of Jefferson and State of Iowa, have invented a new and useful Improvement in Cattle-Stalls, of which the following is a specification.

My invention relates to cattle stalls wherein provision is made to align the cattle forward or back in the stall to correspond with their length and the location of the gutter so that the stall floor may be more easily kept clean, and it consists of the features hereafter set forth and more particularly 10 pointed out in the claims.

In the accompanying drawings forming part of this specification, Figure 1 is a perspective of three sections of stalls embodying the features of my invention. Fig. 2 is 20 a plan view showing two sections of stalls in two different alinements. Fig. 3 is a transverse section on line 3—3 of Fig. 1. Fig. 4 is an enlarged vertical section on line 4—4 of Fig. 3. Fig. 5 is a detail view.

Referring to the drawings, A represents a top rail supported by stall posts B which are braced by stall partitions C, all of which constitute a stall frame in the usual manner. Adjustable bars D arranged in pairs 25 are secured to the stall posts by clamps E, and form additional parts of the stall frame. The ends of these bars are bent at right angles to their bodies which are vertically disposed while the ends assume a horizontal 30 position. At the point where the vertical and horizontal portions join above and below, horizontally disposed members F are connected by castings G thus connecting a pair of the bars D together above and below 35 and forming the alining portions of the frame for each individual stall located between the posts B.

An enlarged detached view of the casting G is shown by Fig. 5, by which it will be 40 seen that this casting consists of a tubular end to embrace the end of the horizontal member F and two brackets g extended at an angle to each other to attach to the vertical and horizontal portions of the bars D. The stanchions S to hold the cattle are attached at their upper and lower ends to the upper and lower members F, preferably near the centers, and the frame may be provided 45 with guide pieces I which are preferably 50 made tubular and are attached to the hori-

zontal members F by clamps i which are preferably adjustable thereon.

The mangers represented by H are formed of sheet metal sides, ends and bottoms, and the inner ends of their sides are 55 hinged at their upper corners to the adjustable bars D by hinge castings J. These castings are arched in the middle and their ends are made to fit the bars D and are secured thereto by clip bolts b. It is preferable that 60 the manger sections should be substantially rectangular; that they should have braces M and that their bottoms should extend up close to the lower horizontal members F. Hooks N may also be mounted on the members F to catch and hold the mangers in elevated position. 70

Cow stalls are generally provided with gutters O to receive the droppings from cows and thus keep the stall floors clean. 75 To accomplish this result satisfactorily, the cows should be alined well on the gutter, but with cows of different lengths it is necessary that the distance between the manger and the gutter shall correspond with the 80 length of the cow. To accomplish this result is the principal object of this invention, and it is accomplished in the following manner:

When the distance between the manger 85 and the gutter does not correspond with the length of the cow, the bolts holding the clamps E are loosened and the horizontal ends of the bars D are slid in the loosened clamps either backward or forward until 90 the proper distance between the manager and the gutter is secured, and then the bolts are tightened to hold the bars D in the proper position. The mangers being connected to the bars D and the stanchions S 95 being connected to the horizontal members F which are also connected to the bars D, the whole will be adjusted back or forward as desired.

The adjusting backward and forward of 100 the stanchion alone is not sufficient, because the cow will always try to aline herself on the manger which contains her feed, and when the stanchion alone is adjusted she will either step backward until her head is 105 against the stanchion or forward until her shoulders come in contact with the stanchion, and in either case, her alinement on the gutter will not be obtained. With my invention, in alining the stanchion and manger 110

together, a perfect alinement of the cow on the gutter will be secured.

It is not necessary to loosen all the bolts holding the clamps E in making adjustments. As shown in Fig. 4 the casting E clamping the bar D is tightened on the upper edge only, while the lower edge is made wide so it will not come in contact with the bar D. Hence the lower bolts do not have to be loosened but can remain tightly clamped to hold the clamps E securely on the posts B in their proper positions while the bars D will be loosened and tightened by loosening and tightening the upper bolts only.

In Fig. 4 one side of the clamp E represented by E' is plain and is not provided with a recess to admit the bar D. This is used at the end of a row of stalls where there is no adjoining stall to require a bar D. In central sections with stalls on both sides of the post B, castings like that shown by E are used on both sides.

What I claim is:

1. In cattle stalls having a series of vertically disposed stall posts suitably supported, vertically disposed bars having their ends bent at approximately right angles to their bodies, said ends being adjustably secured to said posts, and a manger secured to said bars and adjustable therewith.

2. In cattle stalls having a series of vertically disposed stall posts suitably supported, vertically disposed bars having their ends bent at approximately right angles to their bodies, said ends being adjustably secured to said posts, upper and lower horizontally disposed members secured to the upper and lower ends of said bars near the junction of their vertical and horizontal portions, and cattle holding means secured to said horizontal members.

3. In cattle stalls having a series of vertically disposed stall posts suitably supported, vertically disposed bars having their ends bent at approximately right angles to their bodies, said ends being adjustably secured to said posts, horizontally disposed tubular members secured by castings tubular on one end and having brackets on the other end attached to the upper and lower ends of said bars and stanchions secured to said horizontal members.

4. In cattle stalls having a series of vertically disposed stall posts suitably supported, vertically disposed bars having their ends bent at approximately right angles to their bodies, adjustably secured to said

posts, a manger hinged to said bars and cattle tying means secured thereto.

5. In cattle stalls having a series of vertically disposed stall posts suitably supported, vertically disposed bars having their ends bent at approximately right angles to their bodies, adjustably secured to said posts, a manger hinged to the central portions of said bars, horizontally disposed members connected to the upper and lower ends of the bars and stanchions secured to said horizontal members.

6. In cattle stalls having a series of vertically disposed stall posts suitably supported, vertically disposed bars having their ends bent at approximately right angles to their bodies, said ends being secured to said posts by clamps having recesses to receive the ends of the bars, one edge of the recess being wide so it will not bear on the bars while the other is adapted to be tightened on the bars and loosened therefrom, and cattle tying means secured to said bars.

7. In cattle stalls having a series of vertically disposed stall posts suitably supported, vertically disposed bars having their ends bent at approximately right angles to their bodies, said ends being adjustably secured to said posts, horizontally disposed members reaching from one side of the stall to the other, and secured to the upper and lower ends of said bars, a stanchion secured to the central portion of each of said members and a vertically disposed guide bar adjustably secured to each member at each side of the stanchion.

8. A cattle stall comprising posts, a framework, and adjustable connecting means between the posts and the framework, whereby said framework may be adjusted horizontally relative to the posts, and a manger hinged to and carried by said adjustable framework.

9. An animal stall comprising posts, a frame, adjustable connecting means between the posts and the framework whereby said framework may be adjusted horizontally relative to the posts, said frame comprising adjustable bars and horizontal members, a manger hinged to the adjustable bars, the lower horizontal member forming a stop therefor when the manger is in its lowered position, and a stanchion supported by the horizontal members.

WILLIAM LOUDEN.
